[57] CLAIM

The ornamental design for a beverage cooling sleeve, as
shown and described.

DESCRIPTION

FIG. 1 is a top, front, right side perspective view of a
beverage cooling sleeve showing our new design;
FIG. 2 is a rear elevational view thereof;
FIG. 3 is a front elevational view thereof;
FIG. 4 is a side elevational view thereof, the side oppo-
site being a mirror image of the side shown in FIG. 4;
FIG. 5 is a top plan view thereof; and,
FIG. 6 is a bottom plan view thereof.

FIG.1

FIG. 4

FIG. 3

FIG. 2

FIG. 5

FIG. 6
